UNITED STATES PATENT OFFICE.

JOSEPH SACHS, OF HARTFORD, CONNECTICUT, ASSIGNOR, BY MESNE ASSIGNMENTS, TO THE HART & HEGEMAN MANUFACTURING COMPANY, OF HARTFORD, CONNECTICUT, A CORPORATION OF CONNECTICUT.

ANTITHEFT DEVICE FOR INCANDESCENT LAMPS.

1,148,538.

Specification of Letters Patent. Patented Aug. 3, 1915.

Application filed August 26, 1912. Serial No. 716,959.

To all whom it may concern:

Be it known that I, JOSEPH SACHS, a citizen of the United States, residing at Hartford, in the county of Hartford and State 5 of Connecticut, have invented certain new and useful Improvements in Antitheft Devices for Incandescent Lamps, of which the following is a specification.

This invention relates to anti-theft devices 10 for incandescent lamps.

It is a well-recognized fact that lamps are surreptitiously abstracted from their 15 sockets, especially where they are high-priced as is the case with the so-called "tungsten" lamps.

It is the purpose of the present invention to provide means which is capable of inexpensive manufacture and which is certain 20 in action, by which the unauthorized removal of a lamp from its socket can be effectually prevented.

My invention may be embodied in various forms, two of which are herein shown and described, but I do not limit myself to such 25 showing as I may depart therefrom in several particulars within the scope of the invention defined by the claims.

Referring to the drawings: Figure 1 is an elevation partly in section, of an ordinary lamp and socket provided with my 30 anti-theft device. Fig. 2 is a detail view in section showing a portion of the latching and sealing means. Fig. 3 is a detail view in elevation of the same. Fig. 4 shows a 35 lamp and socket the invention being embodied as parts of both.

Like characters refer to like parts throughout the several views.

In Fig. 1 there is shown a lamp 6 and a 40 socket 7 both of standard construction and which therefore require no detailed description. The invention comprises as to one of its broader features, means for preventing the withdrawal of a lamp such as 45 from its socket, such as 7, in connection with means for positively normally preventing releasing movement of said first mentioned means, it being evident that the latter has a releasing movement and that when the 50 same is in such condition, the lamp can be freely taken from its socket. Both said means may vary radically as to character as will be clear from what I have already stated.

The lamp shown in Fig. 1 has a circumferential recess or groove 6' where the shell of the base joins the neck of the bulb and which constitutes a convenient seat for a catch such as the ring 8 which for ease of assemblage is divided or split. Said ring or collar 8 is normally or when in operative relation, immovable in the direction of the longitudinal axis of the lamp, being in fact practically fixed. It is of course obvious that said ring, collar, or projecting catch 65 portion might be integral with the lamp; in fact I show and will hereinafter describe such a construction. One of the parts such as the socket 7 as will hereinafter appear, carries a latch, the other part, (the lamp in 70 the present case), being equipped with a catch engageable by said latch, and the upper surface of such ring or collar 8, conveniently presents such a catch, although this is not essential. The divided band 10 75 answers satisfactorily as such a latch although it could easily be of some other nature. Said latch or band 10 is preferably held normally in fixed relation with the socket 7, and the bead 11 on the external 80 shell 12 of the socket can be advantageously utilized in this connection although this is not material. This structure is of advantage, however, in that said bead 11 is present on standard sockets. Hence said bead 11, 85 presents a suitable catch co-operative with the latch, fitting for this purpose an interior groove 13 in the band 10 which as will be understood is somewhat resilient. Said band 10 is preferably provided with a detent portion which as shown consists of the internal flange or lip 14 adapted to engage the upper face of the flange 8' of the ring or collar 8, and when this relation exists the lamp cannot be withdrawn from its 95 socket. Consequently to remove the lamp from its socket, it is necessary to open said band 10 sufficiently to permit the collar 8 being disengaged from the detent or operative portion 14 as the lamp is unscrewed. I 100 have described one means, which when in operative relation, will prevent withdrawal of the lamp from its socket, and I prefer to associate therewith, means for positively preventing releasing movement of said 105 latching means and as already intimated the same may be of any suitable character.

In the construction shown the latching

band 10 has at its terminals, the outwardly-extending ears or lugs 15 and 16 perforated for the passage of the locking members as the pin 17 which as shown consists of a screw. One of the perforations such as that in the lug 16 has its wall plain while the wall of the other perforation is threaded to receive the threads of the screw 17, which constitutes a simple means of locking the latching band 10.

While the head 19 of the screw 17 might be of any suitable shape, I prefer that it be un-slotted and of a form suitable to receive a wrench, key or equivalent tool; as shown it is polygonal, being triangular. Said head fits within a casing as 20 which may as illustrated, consist of a short tube rigid or integral with the lug or ear 16. This casing or tube 20 acts as one form of guard for said head 19 preventing the operation thereof by ordinary wrenches, pliers, etc., from the side, a special tool as will be clear, being required to remove said locking screw. The latter with its adjuncts already described, under ordinary circumstances, acts with certainty to prevent the wrongful releasing or freeing action of the band 10 or its equivalent.

There may be instances, however, where persons may carry a key or wrench suitable for operating the locking pin or screw 17, and to guard against this possibility, I provide an additional safeguard, in the form of sealing means, as will now appear. The case 20 has its wall diametrically-oppositely perforated as at 21 to receive the wire 22 the ends of which are brought together outside said case, and held against accidental separation, by the fusible seal 22'. The wire 22 constituting part of the sealing means, extends across the case 20 and thereby presents a barrier against access to the screw head 19. To reach said head therefore the wire must be either snipped between the seal and the case or the seal 22' melted, both of which are operations which a thief would not do under ordinary circumstances. Even if he did the band 10 could not be opened sufficiently to permit the withdrawal of the lamp, until the screw 17 was removed and this as already stated, would require a special tool.

The following is one of the several procedures which may be adopted in assembling the parts: The ring or collar 8 ordinarily of insulating material, will be opened slightly and slipped over the base of the lamp until it is received within the angular groove 6' and when freed it automatically closes and hugs the wall of said groove. The latch or band 10 is then slightly opened to receive the shell 12 and is then slipped along until the flange 14 abuts against the bead 11, the band at this time being opened somewhat beyond its normal or locked na-

lotion and its upper edge being separated or spaced from the corresponding edge of the shell 12. The lamp can then be freely inserted in its socket and when the base or connecting portion thereof has bottomed in said socket, the lamp will be latched in such position by drawing the band upward until the bead 11 is opposite the groove 13, the flange 14 being above the flange 8'. The band is then tightened about the socket and lamp and then locked and sealed as already described.

Referring now to Fig. 4, the outer shell 25 of the socket has a prolongation 26 which is slit at 27, the slit or slits as shown, extending well down into the body of said shell. It follows therefore that the extended portion 26 is resilient. Said resilient portion has an inturned flange 28 to snap over the collar 29 of the lamp 30, shown in this case as integral therewith, at about the time that the base portion thereof is bottomed in said socket, so that when said relation is maintained said lamp cannot be taken from its socket. Said extended or resilient portion 26 is also provided with lugs 31 and 31' equivalents of the lugs 15 and 16 already described, and which are provided with the same accessories to which corresponding characters will be applied. After the lamp is introduced into its socket 25 and after the circular flange 28 has snapped over the collar 29, the lugs or ears are drawn together and the locking screw and sealing means applied as already set forth in connection with the other form of the device.

It will be noted that my improved lamp lock comprises two separate and distinct main elements, viz: the lamp catch ring which is preferably split and the locking band (also preferably split) with its catch portion co-operating with the catch ring and the catch portion on the socket. These elements are entirely separate from each other and complete in themselves, being in no way secured one to the other and being held together only when the band is closed and locked around the lamp and socket. By thus providing a lamp lock in which these two elements are entirely separate and unsecured to one another, I am enabled to greatly facilitate the attachment of the lock and also thereby make it possible to use it with a greater variety of lamps and sockets. Both lamps and sockets vary in diameter at the points at which the lock is to be attached. The separate lamp catch ring may be made in different sizes while the locking band may be made in only one size. In using my improved lock, therefore, it is not necessary to provide a variety of differently sized complete locks such as has heretofore been necessary, but it is only necessary to provide a single common locking band and

use therewith a catch ring of the requisite size to properly fit the neck of the lamp.

A further advantage of my construction is found in the facility of attaching the lock which is due entirely to this separate piece 5 construction. The lamp catch ring particularly when made so as to be resilient and hug the neck of the lamp, is first sprung onto the lamp into its proper position seat- 10 ing in the recess at the upper end of the base and hugging the glass of the bulb. The band which is also resilient is then sprung over the catch ring and the complete lamp with its attached catch ring and band is 15 then screwed into the socket, after which the ends of the band are brought together and locked.

What I claim is:

1. An incandescent lamp anti-theft device 10 comprising a split catch ring and a locking band to inclose the ring, the two parts being disconnected to permit the ring to be applied to the lamp independently of the band, the ring when in position surrounding the 15 neck of the lamp above the base thereof and the band having a bearing for the ring.
2. An incandescent lamp anti-theft device 25 comprising a split ring and a split one-piece resilient band disconnected from each other,

to permit the ring to be applied to the lamp 30 independently of the band, the band inclos- ing the ring and the ring when in place en- circling the neck of the lamp and fitting above the base thereof.

3. An incandescent lamp anti-theft device 35 comprising a split catch ring and a split one- piece resilient band disconnected from each other to permit the ring to be applied to the lamp independently of the band, the band having an internal flange to support the 40 ring and also having an internal groove to receive the bead of an incandescent lamp socket.

4. An incandescent lamp anti-theft device 45 comprising a split catch ring of insulating material, and a split resilient locking band, the two being disconnected to permit the ring to be applied to the lamp independently of the band, the ring when in operative posi- 50 tion surrounding the neck of the lamp above and against the base thereof, the band hav- ing a bearing to support the ring.

In testimony whereof I affix my signature in presence of two witnesses.

JOSEPH SACHS.
